UNITED STATES PATENT OFFICE.

JACKSON F. FRAZEE, OF SAN FRANCISCO, CALIFORNIA.

MULTIPLE BALL-BEARING SUPPORT FOR PUNCHING-BAGS.

No. 823,595.

Specification of Letters Patent.

Patented June 19, 1906.

Application filed January 27, 1905. Renewed January 26, 1906. Serial No. 298,063.

To all whom it may concern:

Be it known that I, JACKSON F. FRAZEE, a citizen of the United States, residing in the city and county of San Francisco, State of California, have invented certain new and useful Improvements in Multiple Ball-Bearing Supports for Punching-Bags; and I do hereby declare the following to be a full, clear, and exact description of the same.

10 The present invention relates to an improved form of support for punching-bags, the working parts of which shall be so constructed as to provide ball-bearing surfaces therebetween whereby friction is materially reduced and the several parts permitted free and independent movement in accordance with the direction of strain exerted thereon by the swing of the punching-bag suspended therefrom.

20 To comprehend the invention, reference should be had to the accompanying sheet of drawings, wherein—

Figure 1 is a view illustrating the assembled support secured to an overhead beam or ceiling, the suspension-cord attached thereto at its upper end being partly broken and disclosing a section of the punching-bag secured thereto. Fig. 2 is a detail view, the supporting base-plate, with its depending extension, being sectioned vertically in order to illustrate the connection of the rotatable stem thereto; and Fig. 3 is a plan view of the supporting base-plate.

In the drawings the numeral 1 is used to indicate any suitable form of a supporting base-plate, which base-plate is attached to an overhead beam or ceiling by screws 2 or any other desired form of fastening means. The base-plate 1 is provided with a depending extension 3, within which are located the wear-cups 4 4'. These wear-cups 4 4' provide circular seats for the double series of bearing-balls 5 5', on which rest, respectively, the cones 6 6'. Said cones are fitted on the 45 rotatable stem 7, which extends through the depending extension 3 and is held in place by means of the nut 7', secured to the upper end thereof and located within the extension 3. A swivel connection is thus made with 50 the extensions 3 of the base-plate 1.

The projecting or lower end 8 of the rotatable stem 7 is somewhat enlarged and is formed with an eye 8'. Within this eye or open portion of the enlarged end or head 8 is arranged a series of balls 9, which act as a 55 ball-bearing for the hook member 9', fitted or secured within the eye 8'. By this form of connection between the hook member and the eye 8' there is provided a ball-bearing joint which allows for the free movement of 60 the hook member 9' during the swing of the punching-bag 10 without danger or liability of the same binding or cramping, thus permitting of a uniform movement being imparted to said punching-bag. To the hook 65 member 9' is attached a depending holder 11, which holder receives and retains the upper end portion of the suspension cord or rope 12, to the lower end of which cord or rope there is attached the punching-bag 10.

Having thus described the invention, what is claimed as new, and desired to be protected by Letters Patent, is—

1. A support for punching-bags comprising a suitable base-plate provided with a depending extension, a stem rotatably held within the extension of the base-plate, an eye in the end portion of the stem, a series of bearing-balls held within said eye, a hook member secured within the eye of the stem 75 and working on the bearing-balls therein, and means carried by the hook member for the attaching of one end of a suspension-cord. 80

2. A support for punching-bags comprising a suitable base-plate provided with a depending extension, a stem rotatably held in the depending extension, a series of bearing-balls located within the said extension and against which the rotatable stem works, a hook member for the suspension-cord of a 85 punching-bag movably united to the rotatable stem, and bearing-balls interposed between said hook member and the rotatable stem. 90

3. A support for punching-bags comprising a suitable base-plate provided with a depending extension, wear-cups fitted within the said extension, a series of bearing-balls held within each wear-cup, a stem rotatably held within the extension of the base-plate, 95 100

cones on said stem which work on the bearing-balls, an eye in the lower end or enlarged head of the stem, a series of bearing-balls fitted within the eye of the stem, a hook member working on the bearing-balls of the rotatable stem, and means carried by said hook member for the attachment of the suspension-cord of a punching-bag.

In testimony whereof I have hereunto affixed my signature in the presence of witnesses.

JACKSON F. FRAZEE.
